CLAIM

The ornamental design for a carrying case for mobile phones and credit cards, as shown and described.

DESCRIPTION

FIG. 1 is a perspective view showing my new design;

FIG. 2 is a top plan view thereof;

FIG. 3 is a bottom plan view thereof;

FIG. 4 is a left side view thereof;

FIG. 5 is a right side view thereof;

FIG. 6 is a front view thereof; and,

FIG. 7 is a rear view thereof.

The broken lines depicting a wheelchair and mounting accessories shown in FIGS. 1–7 represent environment that form no part of the claimed design. The broken lines, and unshaded surfaces surrounded by broken lines, depicting a portion of the carrying case for mobile phones and credit cards represent features of the article that form no part of the claimed design.

1 Claim, 6 Drawing Sheets
